SOUND DAMPING DEVICE FOR
MICROPHONESJack A. Hayenga and Frank E. Brooks, Yakima,
Wash., assignors of one-half to Richard O.
Bohannon, Yakima, Wash.

Application February 13, 1936, Serial No. 63,793

7 Claims. (Cl. 181—33)

This invention relates to a sound damping device for microphones or other devices for the transformation of air vibrations or sound waves into any one of several forms of energy.

5 When used with a radio microphone, for example, the improvements increase the energy level of all frequencies picked up, at the lower and higher extremes of the audio range, increases the purity and accuracy of transformation of 10 all frequencies and generally reduces the difficulties encountered with the acoustics of a broadcasting studio.

One feature of the invention resides in arranging on one side of a vibrating member used 15 to transform sound waves into any one of several forms of energy, a series of convolutions of sound absorbing material arranged in such a manner as to reduce the frontal area and the angle of incidence presented to the sound waves approaching the sound absorbing material from 20 the vibrating member, to a minimum; and with alternate convolutions closed with sound absorbing material on the sides away from the vibrating member in such a manner as to form relatively 25 dead air spaces and with the sound absorbing material arranged within a suitable baffle which is attached to the structural member, or members, associated with the vibrating member by means of suitable vibration damping material.

30 The use of the present sound damping device in connection with a radio microphone enables the use of an effective baffle so that the energy level is raised for all frequencies and the discordant reflected waves are eliminated.

35 The more specific objects and advantages will become apparent from a consideration of the description following taken in connection with the accompanying drawing, illustrating an operative embodiment.

40 In said drawing:—

Figure 1 is an end elevation of one form of the invention;

Figure 2 is a side elevation thereof;

45 Figure 3 is a central vertical longitudinal sectional view;

Figure 4 is a central horizontal sectional view taken on the line 4—4 of Figure 1;

Figure 5 is an enlarged detail of the frames and sound absorbing material thereof;

50 Figure 6 is a detail perspective view of one of the frames on which the sound absorbing material is mounted; and

Figure 7 is a fragmentary detail of a modified means for supporting the casing of the invention.

55 Referring specifically to the drawing, wherein

like reference characters designate like or similar parts, 8 designates a casing or enclosure which is made of solid wood, composition material or the like of such thickness, say an inch or more, as to be practically non-resonant at the frequencies in the associated microphone range. 9 designates a hollow tubular pedestal for supporting the casing 8. The microphone 10, of conventional form, is mounted in an opening 11 in one end of said casing, surrounded by vibration damping material 12, such as rubber, felt or the like. The interior of the casing 8, has a lining 13, of sound damping material, such as cloth, batting or the like.

Within the casing, any suitable number of 15 sound damping units 14 are provided. These units are similar in construction and consist of skeleton metallic wire or other frames 15 having parallel rods or wires 16 at the rear thereof and parallel rods or wires 17 at the front thereof, 20 the latter being disposed in planes passing between the planes of the first mentioned wires 16. Sheets 18 of sound deadening material or sound absorbing material are laced alternately over the wires 16 and 17 in accordion fashion, having 25 their ends secured to the adjacent parts of the frame and such ends or the frame secured to the material 13 and the casing 10. To this end, the material 13 and 18 may be glued to each other and to the casing 10, or nails, tacks or other suitable means may be driven through the material 13 into the casing and about the frames. 30

It will be noted that alternate convolutions or valleys of the material 18, at the sides of the frame remote to the microphone are closed by 35 means of strips 19 of sound absorbing material, stitched or otherwise fastened at its sides to the material 18.

Three of the sound damping units 14 are shown in the drawing and the central one is turned at 40 90° to the remaining ones.

The sound absorbing material 13, 18, and 19, for example, may be cotton, bathrobe material constructed with forty-nine warp threads per inch and forty-eight filling threads per inch, 45 manufactured thirty-six inches wide and weighing eight ounces per yard. It is to be understood that any suitable sound absorbing material may be used.

The effect of closing alternate convolutions on 50 the sides of the units 14 away from the microphone is to delay and divert the sound waves traveling that path so that these waves are more effectively damped. In practice, this arrangement is highly successful whereas when all con- 55

volutions are closed, the sound waves are reflected back to the microphone too much and when no convolutions are closed, the damping is insufficient. The purpose of the 90° shift of the central unit 14 is to change the direction of the sound waves so that they are more effectively broken up or damped than would be the case if the convolutions all had the same position.

20 designates an electric conductor from microphone 10, that exits from casing 8 through an insulation walled opening 21 into the support 9 and from thence through an opening 22 in said support.

In Figure 7 is disclosed a modified means for 15 supporting the casing 8 comprising an angular bracket 23 for suspending the casing, the electric conductor being designated 20 that exits through insulated opening 21 and secured to a leg of the bracket 23 by loops 24.

20 It is to be understood that the exact form of the convolutions or pleats may be varied from the simple accordion form shown to more complex forms of circles, zigzags, spirals, etc.

Various changes may be resorted to provided 25 they fall within the spirit and scope of the invention.

We claim as our invention:—

1. A device of the class described comprising a 30 casing in one end of which a microphone is adapted to be positioned, and sound absorbing material in said casing arranged in convolutions and a skeleton support for said material having means to facilitate the lacing and support of the convolutions.

35 2. A device of the class described comprising a casing in one end of which a microphone is adapted to be positioned, said casing being substantially non-resonant to the vibrations of a microphone,

and sound absorbing material in said casing arranged in convolutions and a skeleton support for said material having means to facilitate the lacing and support of the convolutions.

3. A device according to claim 2 having the 5 alternate convolutions at the side remote to that in which the microphone is adapted to be positioned closed by sound absorbing material.

4. A device according to claim 2 having the convolutions extending generally in the direction of 10 the longitudinal axis of the microphone positioning end and the convolutions at the end remote thereto being alternately closed with sound absorbing material.

5. A device of the class described comprising a 15 casing in one end of which a microphone is adapted to be positioned, a skeleton frame within said casing disposed transversely thereof, sound absorbing material laced in convolutions in said frame, alternate convolutions at the side of the 20 frame remote to the microphone receiving end being closed by sound absorbing material.

6. A device according to claim 5, having sound absorbing material lining said casing.

7. A device of the class described comprising a 25 casing in one end of which a microphone is adapted to be positioned, skeleton frames within said casing disposed transversely thereof, sound absorbing material laced in said frames and forming convolutions, the convolutions of one frame being angularly disposed with respect to the convolutions of the other frame, alternate convolutions at the sides remote to the microphone receiving end being closed by sound absorbing material. 30 35
